ELECTRICALLY HEATED BATHTUB

Filed April 13, 1926

K.H. Ober

A technical drawing of a mechanical assembly. It features a horizontal top bar supported by three vertical legs. The leftmost leg is labeled with the number 11. The middle leg is labeled with the number 13. The rightmost leg is labeled with the number 14. The drawing is signed "Watson E. Coleman" and includes the word "Attorney" at the bottom right.

Patented May 15, 1928.

UNITED STATES PATENT OFFICE.

KATHARINE H. OBER, OF BALTIMORE, MARYLAND.

ELECTRICALLY-HEATED BATHTUB.

Application filed April 13, 1926. Serial No. 101,754.

This invention relates to bath tubs and particularly to bath tubs designed for use by invalids and which are particularly adapted for use in hospitals, the general object being to provide a bath tub, the bottom or walls of which may be electrically warmed or heated so as to heat the water in the bath tub to the proper temperature and keep the water warm or hot for a longer time than is possible where water is drawn from the ordinary hot water heating system.

A further object is to provide a bath tub with heating coils disposed beneath the tub for the purpose of heating the tub and keeping the water therein hot or warm for a considerable time, said tub being provided with sprays formed in the side walls of the tub and connected to the usual hot water pipe and also to the cold water pipe.

20 A still further object is to provide means whereby one or more of the heating coils may be disconnected from the source of electricity or connected thereto, to thus decrease or increase the amount of heat supplied to the 25 tub, and also provide for heating certain parts of the tub to a higher temperature than other parts of the tub.

My invention is illustrated in the accompanying drawings wherein:

30 Figure 1 is a longitudinal section through a bath tub constructed in accordance with my invention;

Fig. 2 is a diagrammatic elevation of the water pipes for supplying water to the bath tub:

Fig. 3 is a fragmentary section on the line 3—3 of Figure 1;

Fig. 4 is a fragmentary section on the line 4—4 of Figure 1;

40 Fig. 5 is a section on the line 5—5 of Figure 1;

Fig. 6 is a diagram of the electrical connections of the heating units;

Fig. 7 is a transverse section through the front side wall of the tub showing a door whereby access may be had to the heating units.

Referring to these drawings 10 designates a tub which may be a metal tub, a porcelain lined tub or porcelain tub. This tub is illustrated as having its side and end walls extended from the top of the tub proper downward to the floor as at 11. I do not, however, wish to be limited to this though 55 preferably this form of tub is used. The bottom of the tub 10 is disposed in spaced

relation to the floor, that is the outer wall 11 extends down to the floor thus holding the bottom 12 of the tub raised from the floor and the tub is provided with the usual hot 60 water pipe 13 and the cold water pipe 14. These pipes extend upward at one end of the tub and may be disposed either exteriorly of the end wall 11 at that end or between this wall and the tub proper. These pipes 65 are connected to faucets extending through the wall of the tub preferably adjacent the bottom of the tub so that no water will sputter or splash on the invalid. I have illustrated the bottom of the tub as being 70 provided with inlet openings connected to the pipes 13 and 14, these inlet openings being shielded by a baffle 15 but I do not wish to be limited to this construction.

Extending entirely around the tub is a 75 spray pipe 16 having nipples discharging through perforations 17 in the wall of the tub. This spray pipe is illustrated as being connected both to the cold water and the hot water pipes, there being valves 18 controlling 80 the flow of hot or cold water to the spray pipe, these valves preferably having handles extending through the wall of the tub so that they may be manipulated by a person within the tub. While I have illustrated one spray 85 pipe 16 one or more spray pipes disposed at different levels may be used.

Below the bottom of the tub are a plurality of heating coils or units designated generally 19. These units may be of any suitable construction and each includes a coiled heating wire disposed within an electric insulating body 20. These heating units are disposed beneath the tub and each heating unit at one end is connected to a feed wire 90 21. As illustrated, the other end of each coil is connected by a wire 22 to a switch terminal 23, there being as many of these switch terminals 23 as there are coils, and there being a rheostat switch, as for instance 95 the switch 24, adapted to be shifted so as to connect one or more of these coils to a return wire 25. It will be obvious that by adjusting the rheostat switch 24 that any number 100 of the coils 19 may be connected to the return wire and thus only one or any number of the coils be energized, and either end of the series of heaters can be heated while the opposite end remains cool. This is desirable where a person wants to sit on an end of the 105 tub and heat the soles of the feet without 110 using electric current for heating the entire

bottom of the tub. The wires 21 and 25 will be preferably connected to a plug 26 adapted to be engaged with any service box or socket.

- 5 Preferably the wall 11 of the tub along the front of the tub is so formed to provide a hinged door 11^a as shown in Figure 2, which may be opened to permit access to be had to the heating coils, thus providing for 10 the repairing or replacing of the heating coils when necessary.

I do not wish to be limited to any particular form of electrical heating unit nor to any particular form of switch or to a particular 15 arrangement of the circuit wherein these coils are mounted. It is obvious, for instance, that each of these coils might be controlled by a single switch so that each coil would be separately thrown into circuit 20 if desired. The wires 21 and 25 are designed to be provided with the ordinary plug whereby the series of coils may be plugged into a house electrical circuit.

While I have referred to the use of my 25 heating appliance with a porcelain tub or enamel tub, it will be understood that the bottom of the tub must be of metal, as metal is a good conductor of heat and further because porcelain is liable to crack under 30 heat. It is further to be understood that the heating coils and the electrical connections must be such that the electrical current is not communicated to the tub or to the water therein and that the wires and coils must 35 be thoroughly and entirely insulated from the tub and the water.

I have shown the heating units as being spaced from the bottom of the tub so that there will be no danger of the electrical

current by any chance flowing through the 40 wall of the tub.

I claim:—

1. An electrically heated bath tub comprising an exterior supporting portion adapted to rest on the floor and extending 45 upwardly therefrom and thence inwardly and downwardly to form the tub proper with a space between the bottom and sides of the interior portion of the tub and the floor and around the sides of the tub and 50 said exterior supporting portion, a series of electric heaters in the space at the bottom of the tub and extending substantially from one end to the other thereof, and means for energizing one or any number of the heaters 55 of said series for heating the air in the space at the bottom and around the sides of said tub.

2. An electrically heated bath tub comprising a tub proper, an exterior supporting wall 60 extending around the tub proper in spaced relation to the walls of the latter and provided with an inwardly extending upper part that connects with the top of the tub proper and supports the latter so its bottom 65 is in a higher plane than the lower edge of the exterior supporting wall, the said lower edge being adapted to rest on a floor and support said bottom of the tub proper in spaced relation to the floor, whereby a closed 70 heating space is provided under and around the tub proper, and electric heating means in said closed heating space and provided with controlling means for controlling the heat under and around the bath tub proper. 75

In testimony whereof I hereunto affix my signature.

KATHARINE H. OBER.
